DESIGN FOR A PIANO CASE

Wilbur M. Day, Norwood, Ohio, assignor to The Baldwin Company, Cincinnati, Ohio

Application August 15, 1940, Serial No. 94,438

Term of patent 7 years

To all whom it may concern:

Be it known that I, Wilbur M. Day, a citizen of the United States, residing at Norwood, in the county of Hamilton and State of Ohio, have invented a new, original, and ornamental Design for a Piano Case, of which the following is a specification, reference being had to the accompanying drawings, forming part thereof.

In the drawings:

showing my design in closed position, with the music desk and fallboard lowered.

Figure 2 is a perspective view of the design, in opened position, the music desk and fallboard being raised.

I claim:

The ornamental design for a piano case, as shown.

WILBUR M. DAY.
